UNITED STATES PATENT OFFICE.

RALPH L. QUASS, OF NEW YORK, N. Y., ASSIGNOR TO WESTERN ELECTRIC COMPANY,
OF NEW YORK, N. Y., A CORPORATION OF ILLINOIS.

TELEPHONE SYSTEM.

1,163,852.

Specification of Letters Patent. Patented Dec. 14, 1915.

Application filed May 1, 1914. Serial No. 835,750.

To all whom it may concern:

Be it known that I, RALPH L. QUASS, a citizen of the United States, residing at New York, in the county of Bronx and State of New York, have invented a certain new and useful Improvement in Telephone Systems, of which the following is a full, clear, concise, and exact description.

This invention relates to telephone systems, and more particularly to such systems for use in inter-connecting central offices at which terminate a plurality of telephone lines.

The object of this invention is the production of improved signaling means for such telephone systems.

In accordance with one feature of this invention, a two-way trunk circuit is provided, with means at each end for automatically applying ringing current to the trunk circuit for a definite period, for operating a signal at the other end of the circuit upon connecting the link conductors with the trunk circuit.

This invention will be more fully understood by reference to the drawings showing one embodiment of the invention, in which all apparatus is shown in its normal and unactuated condition, and wherein,—

Figure 1 shows a subscriber's line terminating at a central office, and link conductors and a portion of a trunk circuit at the central office; and Fig. 2 shows a subscriber's line terminating at another central office, and line conductors and a portion of the above mentioned trunk circuit thereat, the conductors of the trunk circuit being joined to connect the two central offices.

In the drawings there are shown subscribers' stations A and B terminating at central offices C and D respectively. A trunk circuit E joins the two central offices, at each of which is shown a cord circuit. It is believed that this invention will be fully understood from a description of the operation of the system shown in the drawings, and it will be so described.

It will be assumed that subscriber A desires to converse with subscriber B, and it will be furthermore assumed that A has signaled central office C and that the operator at C has answered and has been informed that the wanted line is that of subscriber B terminating at another central office D. The operator at C thereupon inserts the calling plug of the cord circuit into jack 5 of the

trunk circuit E joining the central offices C and D, completing a circuit from the live pole of battery 6 through supervisory signal 7, winding of relay 8, over conductor 9, 60 sleeve contacts 10 and 11 of the calling plug and the jack 5, conductor 12, and through the winding of relay 13 to ground. Current in this path operates the supervisory signal 7 and actuates relays 13 and 8, which latter relay in operating disconnects the operator's telephone set from the talking strands of the cord circuit, and completes a circuit from the live pole of battery 20 through the winding of relay 21, normally 70 closed contacts 22 of relay 23, and 24 of relay 25, and normally open contact 26 (now closed) of relay 8 to ground. Current in this path actuates relay 21, completing a circuit for a source of ringing current 28 75 through the winding of ringing relay 25, normally open contact 29 (now closed) of relay 21, ring contacts 30 and 31 of the calling plug and the jack 5, conductor 32, winding of low resistance relay 33, normally 80 closed contact 34 of relay 35, conductor 36, tip contacts 37 and 38 of the jack 5 and the calling plug, and normally open contact 39 (now closed) of relay 31, to ground. Current in this path actuates relays 25 and 33. 85 Relay 25 in operating opens the normal shunt about the winding of relay 23, permitting relay 23 to operate, lock itself up and release relay 21, which establishes the continuity of the talking strands of the cord circuit. Relay 33 in operating completes two circuits, the first from live pole of battery 42, through the winding of quick-operating and slow-releasing relay 43, conductor 44, and normally open contact 45 (now closed) of relay 33 to ground. Current in this path actuates relay 43, completing a circuit for a source of ringing current 46 90 through normally open contact 47 (now closed) of relay 43, conductors 48 and 49, normally closed contacts 50 of relay 51, condenser 52, a winding of relay 53, conductors 54 and 55, and normally open contact 56 (now closed) of relay 43 to ground. Current in this path actuates relay 53 which locks up over a circuit from the live pole of battery 60, through a winding of relay 53, 100 normally open contact 61 (now closed) of relay 53, and normally closed contact 62 of relay 51 to ground. Actuation of relay 53 also completes two other circuits, one from the live pole of battery 63, through signal 105

64, and contacts 61 and 62 to ground operating the signal 64, and the other from the live pole of battery 65, through a winding of relay 66, and contacts 61 and 62 to ground 5 actuating relay 66, which opens its normally closed contacts 67 and 68 and closes normally open contacts 69 and 70. At the time of completing a circuit through relay 43, a circuit was also completed from the live pole 10 of battery 74, through a winding of relay 35, normally closed contact 75 thereof, conductor 44, and normally open contact 45 (now closed) of slow-operating relay 33 to ground. Current in this path actuates relay 15 35, completing a locking circuit therefor from battery 74, through a winding of relay 35, normally open contact 76 (now closed) thereof, conductor 77, and normally open contact 78 (now closed) of relay 13 to ground. Relay 35 in operating breaks the 20 circuit of slow-release relay 33, which releases and breaks the circuit of relay 43. Relay 43 in releasing disconnects the source of ringing current 46 from the conductors 25 of the trunk circuit. Actuation of relay 35 also closes normally open contact 79 in a section of the talking circuit.

It will be noted that through the quick-operating feature of relay 43, the slow-operating feature of relay 35, the slow-releasing feature of relay 33, and the slow-releasing feature of relay 43, these relays when actuated coöperate to maintain the source of ringing current 46 connected to conductor 35 48 of the trunk circuit for a definite period of time, which insures the operation of signal 64 at the central office D.

The operator at central office D observing the signal 64, inserts her answering plug of 40 the cord circuit into jack 85 of the trunk circuit, completing a circuit from battery 86, through signal 87, normally closed contact 88 of relay 89, winding of relay 90, conductor 91, sleeve contacts 92 and 93 of the answering plug and the jack 85, conductor 94 and winding of relay 51 to ground. Current in this path operates signal 87, actuates relay 90, placing the operator's telephone set 45 across the talking strands 95 and 96 of the cord circuit, and actuates relay 51. Actuation of relay 51 completes a circuit from the live pole of battery 97, through a winding of relay 98, normally open contact 99 (now closed) of relay 51, conductors 49, 48 and 50 100, normally open contact 101 (now closed) of relay 13, winding of relay 105, conductors 106, 55 and 54, the other winding of relay 98, and normally open contact 107 (now closed) 55 of relay 51 to ground. Current in this path 60 actuates relay 105, closing normally open contact 108 in a section of the talking circuit, and relay 98 closing normally open contact 109 in another section of the talking circuit. Closure of contact 108 completes a 65 circuit from the live pole of battery 110,

through the winding of supervisory relay 111, ring contacts 30 and 31 of the calling plug and the jack 5, conductor 32, contacts 108 and 79, conductor 36, tip contacts 37 and 38 of the jack 5 and the calling plug, and conductor 112 to ground, actuating relay 111 and effacing the supervisory signal 7 by placing a low resistance shunt 115 about it. Similarly, closure of contact 109 completes a circuit from the live pole of battery 116, 70 through the winding of supervisory relay 117, ring contacts 118 and 119 of the answering plug and the jack 85, conductor 120, contacts 109 and 70, conductor 121, and tip contacts 122 and 123 of the jack 85 and the 75 answering plug to ground, actuating relay 117 and effacing the supervisory signal 87 by placing a low-resistance shunt 124 about it. A condenser 125 is shunted about relay 98 to provide a path for the talking current. 80

After inserting the answering plug of the cord circuit at central office D into the jack 85, the operator inquires of subscriber A the desired number, and finding it to be that of subscriber B, completes the connection in 90 the usual manner. The operator's telephone set at central office D is removed from the talking strands of the cord circuit thereat in a manner similar to that described for central office C, and the application of ringing 95 current to the called subscriber's line is likewise accomplished in a similar manner. The ringing current is removed from the called subscriber's line by the removal of the receiver from the switchhook at B, which completes a path of low resistance for the ringing current, and actuates a ringing relay in the cord circuit, this relay and other apparatus associated therewith functioning in exactly the same manner as that described in 100 the cord circuit at central office C. 105

When the conversation between the two connected subscribers is concluded, the subscribers restore the receivers to the switchhooks, which opens the circuits from batteries 110 and 116 over subscribers' lines A and B, respectively, permitting the operation of supervisory signal 130 in the answering end of the cord at central office C, and supervisory signal 131 in the calling end of 110 the cord at central office D. Signal 130 being associated with that end of the circuit known as the "originating end", acts as a disconnect signal for the operator at central office C, who withdraws both plugs of the 115 cord. Withdrawing of the calling plug from jack 5 deenergizes relay 13, opening contacts 78 and 101. The opening of contact 78 releases relay 35, and of contact 101 releases relays 105 and 98. Release of relay 98 120 opens the circuit from battery 116 through supervisory relay 117, which releases and operates supervisory signal 87. Both signals 87 and 131, being operated, act as disconnect signals to the operator at the central 125 130

office D. This operator now withdraws both plugs of the cord, thereby permitting all apparatus to be restored to normal condition.

The system embodying this invention has 5 been described as operating in one direction. It is to be understood that the trunk circuit is adapted to function properly when a call originates at either end. To this end both ends of the trunk circuit are similarly 10 equipped, a signal 135, condensers 132 and 133, and relay 136 at central office C, corresponding to the signal 64, the condensers 52 and 125 and the relay 53 at central office D, also a slow-releasing relay 137, a quick- 15 operating and slow-releasing relay 138, and the slow-operating relay 66 at the central office D, corresponding respectively to the relays 33, 43 and 35 at the central office C, and performing the same functions when a 20 call originates at the central office D.

At both of the central offices there is shown a plurality of batteries, but these may be combined into a single central battery at each office, and such is the usual 25 practice. At each central office there are shown two sources of ringing current, and likewise these may be combined into a single source at each office, such being the usual practice.

30 What is claimed is:

1. A telephone system comprising subscribers' lines terminating at a central office, link conductors thereat for interconnecting said lines, a source of ringing current at the central office, a second central office, a signal thereat, a trunk circuit joining said offices, and slow-releasing and quick and slow-operating relays associated with 35 said trunk circuit actuated and coöperating when said link conductors are connected with said circuit to connect said ringing current to said circuit for a definite period of time for operating said signal.

40 2. A telephone system comprising central

offices, subscribers' lines terminating thereat 45 and link conductors thereat for interconnecting said lines, sources of ringing current and signals at said offices, a trunk circuit joining said offices, and slow-releasing and quick and slow-operating relays associated 50 with said trunk circuit actuated and cooperating when the calling end of a set of said link conductors at either of said offices is connected therewith to connect said source of ringing current thereat with said 55 circuit for a definite period of time for operating said signal at the other of said offices.

3. In a telephone trunk circuit, a circuit formed of main conductors, circuits at each 60 end thereof formed of auxiliary conductors, a signal and a plurality of switching devices included with said auxiliary circuits, a source of control current and a source of ringing current included with said 65 auxiliary circuits; a telephone exchange system at each end of the trunk circuit including link circuits adapted to be connected with the trunk circuit, and means controlled by said switching devices rendered 70 operative when a link circuit is connected with either end of the trunk circuit to complete a cycle of five successive operations, first, to interrupt the continuity of the main conductors, second, to include said ringing 75 current with the main conductors, third, to operate the signal at the other end of the trunk circuit, fourth, to disconnect the ringing current from the main conductors, and fifth, to reestablish the continuity of said 80 main conductors.

In witness whereof, I hereunto subscribe my name this 29 day of April, A. D., 1914.

RALPH L. QUASS.
